PROCESS FOR INHIBITING FOAMING IN
STEAM BOILERSPaul G. Bird and Arthur L. Jacoby, Western
Springs, Ill., assignors to National Aluminate
Corporation, Chicago, Ill., a corporation of
DelawareNo Drawing. Application September 19, 1942,
Serial No. 459,012

4 Claims. (Cl. 252—321)

1

The present invention relates to antifoaming compositions which are used in steam boilers and similar steam generators, evaporators, etc., to overcome the tendency of the water therein to foam and hence to bring about the priming of the steam generator or the like.

One of the objects of the present invention relates to a liquid suitable for the generation of steam in steam generators and comprising water containing therein a very small quantity of an N,N'-disubstituted diamide of an organic dibasic acid, whereby, when such water is heated to the boiling point in a steam boiler or other generator, being thereby evaporated, the concentration of solids therein will not bring about excessive foaming and the resulting priming, these compounds being substantially nonvolatile with the steam and stable, so that they will be retained by the water and neither they nor their decomposition products will appear in the steam and the resulting condensation thereof.

It is well known in the operation of steam boilers, such as in electric power plants, railroad locomotives and the like, or in evaporators, that the water therein, even though initially it shows very little tendency to foam, will, when the amount of total solids therein approaches a relatively high concentration, develop a very decided tendency to foam. When this occurs, considerable quantities of water are physically carried out of the boilers or evaporators with the steam, thus appearing in the steam lines and in the eventual condensate. Such priming has many disadvantages because it tends to contaminate the steam lines, to plug or corrode the valves, and under serious conditions may even impair the cylinders and piston rods of the steam engines, or the impeller blades of turbines in which the steam is used for the generation of power. Attempts have been made in the past to control this foaming, either by excessive blowdown of the boilers or by the injection thereinto of such materials as castor oil, tallow, and the like. While these fatty materials have some small degree of efficiency, they are, on the other hand, quite deficient in that they introduce new difficulties which, in some instances, are worse than the conditions they are intended to cure. In the first place, these fatty acids or glycerides are unstable under the conditions existing in the boilers, particularly as the pressure and temperature increase, the high temperatures leading to rapid decomposition of the glycerides, which, if anything, will tend to increase the foaming and priming difficulties. Furthermore, in many instances certain of the decomposition prod-

ucts thus produced, or sometimes even the materials themselves, have a definite volatility with steam and will, therefore, steam-distil out of the boilers, thus appearing in the steam and in the condensate. This, of course, is also very undesirable. Furthermore, such types of antifoaming agents usually have to be employed in relatively large quantities, adding not only to the expense but also to the inconvenience of operating the steam generators; and those which have a tendency to decompose do so quite rapidly, and hence their effectiveness is of short duration, which therefore necessitates the continual charging into the boilers or other steam generators of relatively large amounts of these older antifoaming agents. Moreover, such antifoaming agents are difficult to use because the amounts in which they are efficacious are very critical, and any over-dosage usually aggravates the difficulty instead of curing it.

Applicants have now discovered, however, that there is a series of compounds which may be broadly designated as N,N'-disubstituted diamides of organic dibasic acids, wherein the substituent groups may be derived from aliphatic primary or secondary amines, or amine-containing bodies; in which the dibasic acids may be either aliphatic, aromatic, or aryl-aliphatic, and may contain hetero atoms between the carboxyl groups; and the molecular weight and configuration conform to certain general specifications; all as more fully described hereinafter, which are highly efficacious to suppress foaming.

The materials employed in the practice of the present invention may be represented by the general formula:

wherein R and R' are aliphatic radicals derived from aliphatic primary or secondary amines or from more complex aliphatic and arylaliphatic amine-containing bodies as, for example, alpha-alkylbenzylamines, C-alkylanilines, monoacylalkylenediamines, alkylalkylenediamines, partially acylated polyalkylenepolyamines, monoacylpiperazines, monoacylhydrazines, and the like; and X is an alkylene or arylene radical which may contain hetero atoms, so that the group —OCXCO— represents the diacyl radical of a dibasic carboxylic acid. The radical —OCXCO— may thus be the residue of a dibasic acid such as adipic, pimelic, suberic, sebatic, azelaic, brassilic, japanic, phthalic, terephthalic, and naphthalic. It will be obvious that when the amide linkages are formed

from secondary amine groups, the hydrogens of the above general formula will be absent.

It has been found that, for the materials of this invention to possess the desired efficacy, it is necessary that the total number of carbon atoms in the derivative be at least about 34.

Some specific compounds which have been prepared and found of value include the diamyl, ditetradecyl, dioctadecyl, and didioctadecyl derivatives of sebacic diamide; the dihexadecyl derivatives of the diamides of adipic, azelaic, and suberic acids; the dioctadecyl derivatives of the diamides of pimelic and terephthalic acids; and the didioctadecyl derivative of adipic diamide.

The compounds of this invention may be obtained in a variety of ways, one of the simplest being to react the dibasic acid, or the halide thereof, with the amino material in almost theoretical proportions, so as to obtain the amide by the elimination of water or hydrogen halide, respectively. The examples given below show methods employed in preparing these materials.

Example 1.—A mixture of 24.2 grams of octadecylamine and 8.1 grams of sebacic acid was heated with stirring at 150°–160° C. for 3 hours. When cool, the product was a hard tan wax.

Example 2.—A mixture of 9.6 grams of amylamine and 10.1 grams of sebacic acid was heated with stirring at 150°–160° C. for 3 hours. When cool, the product was a brown wax.

Example 3.—A mixture of 7.8 grams of pimelic acid and 13 grams of octadecylamine was stirred for 3 hours at 150°–160° C. When cool, the product was a brown wax.

Example 4.—A mixture of 6.1 grams of sebacic acid and 12.8 grams of tetradecylamine was stirred for 3 hours at 150°–160° C. When cool, the product was a dark brown wax.

Example 5.—A mixture of 5.9 grams of adipic acid and 19.3 grams of hexadecylamine was stirred for 3 hours at 150°–160° C. When cool, the product was a pale yellow wax.

Example 6.—A mixture of 7.5 grams of azelic acid and 19.3 grams of hexadecylamine was stirred for 3 hours at 150°–160° C. When cool, the product was a high-melting tan wax.

Example 7.—A mixture of 5 grams of suberic acid and 13.8 grams of hexadecylamine was stirred for 3 hours at 150°–160° C. When cool, the product was a high-melting tan wax.

Example 8.—A mixture of 4.4 grams of adipic acid and 30.7 grams of mixed amines, containing approximately 70% diacetadecylamine and 30% tertiary octadecylamine, was stirred for 3 hours at 150°–160° C. When cool, the product was a brown wax.

Example 9.—A mixture of 3.3 grams of terephthalic acid and 10.6 grams of octadecylamine, plus 5 c. c. of heavy paraffin oil, was stirred for 3 hours at 150°–160° C. When cool, the product was a tan wax.

Example 10.—A mixture of 4.1 grams of sebacic acid and 29.3 grams of the mixed amines of Example 9 was stirred for 3 hours at 150°–160° C. When cool, the product was a brown wax.

The herein described compounds, while not ordinarily considered as soluble in water to any great extent, may be suitably dispersed in water or emulsified therewith, so that effective amounts thereof may be introduced and be present in the water within the steam generator under operating conditions. The emulsifying or dispersing agent used must, however, be of a kind that does not cause foaming, either by itself or by its decomposition products. The compounds may be used

conjointly with each other as well as with other known antifoaming agents, such as, for example, castor oil.

The amounts of the above mentioned N,N'-disubstituted diamides of organic dibasic acids which are required are extremely small, and in general one grain per gallon is ample. For many purposes, however, amounts of as little as $1/100$ grain per gallon in the feed water will still give valuable results, and the amounts may be even further reduced. Depending of course upon the degree of concentration of solids, the dosage may be varied, but one grain per gallon is about as much as would ever have to be used even under serious conditions, and for many purposes $1/100$ grain per gallon and even less can be used. The process is particularly effective at pressures of about 250 pounds per square inch.

The introduction of the antifoaming compounds of the present invention into the boiler may be accomplished in a number of ways. Thus, the antifoaming compositions may be dispersed or physically mixed with, say, sodium carbonate or some other material used for treating the boiler water and pumped with the feed water into the boiler by means of either an injector or a feed water pump. The compounds may also be dissolved in suitable organic water-miscible solvents such as alcohols, ethers, ketones, etc., and introduced in small measured amounts into the feed water entering the boiler. Suitable mechanical measuring devices which will periodically or continuously inject the required dosage of the antifoaming compounds into the feed water may be used, so that the introduction will be more or less in proportion to the steam consumption to which the steam generator is subjected. Another manner of introducing the antifoaming compounds is to form an emulsion thereof in water and then feed said emulsion either directly into the boiler or the feed water lines leading to it. The invention therefore is not to be limited by the manner of introduction of the antifoaming composition but rather is to be construed in the terms of the hereunto appended claims.

We claim:

1. The method of generating steam which comprises boiling, under superatmospheric pressure conditions, water containing an amount of total dissolved solids, tending to produce foaming and priming, and a quantity of an N,N'-disubstituted diamide of an organic dibasic acid which is a condensation product of about two moles of an amine selected from the group consisting of primary and secondary aliphatic amines with about one mole of an organic aliphatic dibasic acid having 6 to 10 carbon atoms, the total number of carbon atoms in said condensation product being at least 34 and said quantity being sufficient to substantially inhibit said foaming and priming.

2. The method of generating steam which comprises boiling, under superatmospheric pressure conditions, water containing an amount of total dissolved solids tending to produce foaming and priming, and a quantity of the condensation product of about 2 mols of octadecylamine and about 1 mol of sebacic acid, said quantity being sufficient to substantially inhibit foaming and priming.

3. The method of generating steam which comprises boiling, under superatmospheric pressure conditions, water containing an amount of total dissolved solids tending to produce foaming and priming, and a quantity of the condensation

product of about 2 mols of hexadecylamine and about 1 mol of azaleic acid, said quantity being sufficient to substantially inhibit foaming and priming.

4. The method of generating steam which comprises boiling, under superatmospheric pressure conditions, water containing an amount of total dissolved solids tending to produce foaming and priming, and a quantity of the condensation product of about 2 mols of hexadecylamine and about 1 mol of suberic acid, said quantity being sufficient to substantially inhibit foaming and priming. 10
